UNITED STATES PATENT OFFICE.

AMÉDÉE CONSTANT SNYERS, OF NEW ORLEANS, LOUISIANA.

CENTRIFUGAL DRYING MACHINE.

Application filed October 19, 1922. Serial No. 595,595.

To all whom it may concern:

Be it known that I, AMÉDÉE C. SNYERS, a subject of the King of Belgium, residing at New Orleans, in the parish of Orleans and 5 State of Louisiana, have invented certain new and useful Improvements in Centrifugal Drying Machines; and I do hereby declare the following to be a full, clear, and exact description of the invention, such as 10 will enable others skilled in the art to which it appertains to make and use the same.

The present invention relates to centrifugal apparatus, as used to separate solids from the liquids in mixtures of these two 15 constituents. The invention aims at providing an apparatus that is continuous in operation and self-discharging, that is, that, with the centrifugal rotating uninterruptedly, the mixture can be admitted into it in a continuous stream, separated solids being at the 20 same time automatically and continuously discharged thus avoiding the necessity of first loading the centrifugal with a sufficient quantity of the mixture, starting it in motion, after a suitable interval of time stopping the centrifugal and thereupon discharging the solids, these operations being repeated for every load of mixture.

The principal object of the invention is 30 thus to provide a device which will continuously propel the solids, inside the centrifugal, toward the outlet and there eject them.

Another object is to provide means to automatically operate said device.

Still other objects are to adapt the general 35 form of the centrifugal to operate in combination with said device.

With the foregoing and other objects in view, the invention will be more fully described hereinafter, and will be more particularly pointed out in the claims appended hereto.

In the drawings, wherein like symbols 45 refer to like or corresponding parts through out the several views.

Figure 1 is a vertical section taken through a centrifugal apparatus constructed according to the present invention.

Figure 2 shows an elevation of the dis- 50 charging apparatus turned at right angles to Figure 1.

Figure 3 is a top plan view of the device.

Figure 4 is a perspective view of the cas- 55 ing.

Figure 5 is a section through the drive shaft with the driving vanes removed.

Figure 6 is a plan view of the drive controlling means showing the vanes.

Figure 7 is a vertical section showing a 60 modification, and

Figure 8 is a horizontal section taken through the device shown in Fig. 7.

Referring more particularly to the drawings 1 is the axle or shaft receiving the driving power, and attached to the stationary frame of the centrifugal. This axle is connected to the bottom 2 of the centrifugal basket, whose vertical wall 3 is perforated and provided with the usual inner filtering lining in order to allow the molasses separated from the massecuite to be thrown through the wall, while retaining the sugar crystals. The upper edge of wall 3 presents an outwardly directed flange 4. The stationary casing 5 around the basket 75 has an inward flange 6 just below flange 4, so as to practically close the upper space between the basket and casing. The bottom of the casing presents an outlet 7 for the molasses. Around the casing 5 is built an annular channel consisting of a vertical wall 10 having the shape of a cylinder cut obliquely, and whose lower oblique edge is connected to the casing by a flange 11 forming the bottom, thus constituting around 80 each half of the casing a steeply inclined channel leading to the outlet or spout 12.

To the upper edge or wall 10 is attached an inwardly and upwardly directed annular flange 13, surrounding and overhanging flange 4, of the basket and located at such a level as to catch the sugar centrifugally ejected over the flange 4, at the same time deflecting it downwardly and breaking its impact. Around the inner wall 95 of the casing is attached an annular flange 8 directed inwardly and upwardly, and forming an annular gutter leading the washings to an outlet 9 as will be explained.

Around the axle 1 is fitted a sleeve or hollow axle 14 capable of turning freely on axle 1 and resting on shoulder 15 disposed on bottom 2 of the basket and serving as a bearing. Inside the basket, axle 14 supports an appropriate number of radial frames 100 composed each by radial arms 16 and 17 supporting the vertical bar 18. Two such frames are represented in the instance shown. The bars 18 extend practically the entire height of wall 3, parallel and close 105 thereto. To their outer surfaces are attached a series of blades 19, which extend very 110

close to the wall 3, without however actually touching it. These blades are disposed obliquely relatively to the horizontal plane and to the zones they engage along the wall 3. In this connection see Figure 2. The 5 blades incline downwardly relatively to the direction of their motion, the direction of motion being indicated by the arrow also in Figure 2. The front or cutting edge is thus lowermost, and when cutting or plowing through the mass clinging to the wall 3, their thrust on this mass has thus an upward component which tends to lift it vertically.

The blades of each set are superposed and 10 parallel and they thus engage and lift simultaneously a vertical strip of mass extending the entire height of the wall. As appears in Figure 3, the shape of the blade in plan is substantially rectangular, they having 15 their outer edges rounded so as to follow the form of wall 3, and they have an oblique front edge for better penetrating. Their number, shape, size and pitch are such as are best calculated for the maximum of 20 efficiency and a minimum of resistance. Now it will be understood that the basket 3, although represented cylindrical, may have other forms, such for instance as the frustum of a cone, the discharger, comprising 25 the frames made up of the arms 16, 17 and 18 with the blades 19, of course following the shape of the basket. At the upper part 30 of the basket an annular bowl 20 is formed around the hollow shaft 14 and connected thereto by its bottom. The lateral wall of 35 the bowl may be conical as represented or of any other suitable shape for preventing the massecuite from being forced over its upper edge by the centrifugal force.

40 At the junction of the lateral wall and the bottom of the bowl are attached a suitable number of pipes 22 opening into said bowl, for instance one pipe being provided for each set of blades 19 and located near the radial plane comprising said blades. The pipes extend downwardly and outwardly in such a way that their lower mouths open in front of the zone of the 45 basket wall engaged by the lowermost blade 19 and at such distance from said wall as not to come into contact with the massecuite deposited thereon; further, the mouths being located directly behind the lowermost blade 50 19, relatively to the direction of the latter's motion.

Around the bowl is built an annular trough 23, whose upper face is partly closed by an inward flange, thus leaving between 55 the latter and the guard an annular open space, above which terminates a suitable water pipe 24. Attached to the periphery of trough 23 and opening therein, are a convenient number of radial pipes 25, whose 60 outer ends are bent down and closed at the

extremity, while the outer faces of the bent parts 26, facing the wall 3, are perforated as seen in section on the left side of Figure 2. The parts 26 are so located as to face wall 3 just a little above the level of the 70 gutter 8.

The upper arms 16 of the discharger frames are conveniently attached to trough 23, while the lower arms 17 are attached directly to axle 14. At the upper end of 75 hollow axle 14 are attached two horizontal radial arms 27, from each of which is suspended a wing or vane 28, of suitable size and shape, as by means of hinges 29. The wings are able to swing freely around the arms, while adequate means are provided to prevent the wings from slipping off the arms under the centrifugal force. Under the wings and around axle 14 is disposed 80 an annular sliding organ 30, whose upper surface presents at the periphery two diametrically opposed wedge-shaped lugs 31 having their oblique faces in front relatively to the direction of rotation. The organ 30 has a central opening and into the opening project two opposed, longitudinal, keys 32, which engage in corresponding longitudinal slots 33 formed in hollow axle 14. These slots being longer than the keys, the organ 30 is thus capable of sliding up 85 and down axle 14, but it is compelled to rotate with said axle. Organ 30 is supported at its inferior face by suitable ball or roller bearings represented in the present instance by balls 34 running in complementary races formed in the lower face of part 30 and the upper face of an annular ball cup 35 which surrounds axle 14 but without being in contact with it. This ball cup is provided with two opposed lateral trunnions 36 which engage in slots provided in the ends of the prongs 37 of a forked lever 38 fulcrumed at 39 on a suitable bracket 40 attached to the frame of the 90 centrifugal.

The lower edge of each wing 28 rests against the oblique face of corresponding lug 31 and is thus pressed firmly against the latter by the resistance of the air, when revolving. It is thus seen that by acting on lever 38, the ball cup and consequently organ 30 can be raised or lowered thereby causing the lugs 31 to engage more or less the wings 28, in this way modifying at 95 pleasure their inclination and consequently their resistance to the air, when rotating. Convenient means are provided to lock the handle of lever 38 to the frame in any given position.

The operation of the invention is as follows:

When the centrifugal is empty, the hollow axle 14 and all the parts attached thereto are practically independent from the motion of the basket. A quantity of masse-

uite may be poured in the basket to start the movement. Centrifugal being set in motion, massecuite is admitted through spout 21, and is delivered thereby into the 5 bowl 20, wherein it is whirled to the periphery, being forced down the pipes 22 and made to issue from the lower ends of these pipes and against the basket wall behind the lowermost blades 19 thus constantly 10 refilling the empty space just created by the lifting action of said blades. As soon as there is sufficient massecuite and the blades 19 of the discharge become embedded in it, this massecuite locks the discharger to the 15 basket and causes it to revolve with the latter. But now the air resistance encountered by the wings 28 retards the rotation of the discharger which begins to revolve relatively to the basket, causing the blades 19 to go 20 through the mass. At the same time, owing to their inclination, each of these blades lifts successively all the parts of the annular zone or strip of mass which it engages, which is possible from the fact that each 25 blade, beginning with the uppermost, by lifting the mass creates under it an empty space ready to receive the mass lifted by the next lower blade. Thus the whole coat of mass lining wall 3 is gradually propelled 30 upwards, at the same time becoming purged sugar, as it is gradually deprived of the molasses, the molasses of course being forced by the centrifugal power through the perforated wall 3 and collected in the casing 35 5, where it escapes through outlet 7 and 9.

When the sugar reaches the level of flange 4, the topmost zone is lifted by the topmost blade 19 above said flange and is ejected against the flange 13 which directs 40 such purged sugar crystals into the channel formed between walls 6 and 10. The steep bottom 11 of this channel, which is most plainly seen in Figure 4 affects a quick movement of the sugar to the escape outlet 12. When it is necessary to wash the sugar, the work is regulated so that the massecuite is practically deprived of its molasses when it reaches the level of the gutter 8. Water is admitted through pipe 44 to the bowl 23 in a continuous stream. The water is at once forced by the centrifugal through pipes 25 down to their perforated extensions 26 and through the perforations, to be forcibly projected against the 45 sugar. The resulting washings traverse wall 3, are collected in casing 5 above gutter 8, drip down into said gutter and flow off through outlet 9, being thus automatically collected 50 separately from the pure molasses. In this case all of the molasses is collected in the casing 5 below the gutter 8 and evacuated through the outlet 7.

The steadily entering flow of massecuite from spout 21 continuously refills the empty 55 space created at the bottom of wall 3 by the

lower blades of the discharger, and it is thus seen that all operations of charging the centrifugal, purging the massecuite, eventually washing the sugar and discharging the latter from the basket, can proceed in 70 a continuous and automatic manner. The proper work required from the centrifugal is obtained by regulating the admission through spout 21, and the speed of the discharger relatively to the basket, this latter 75 being done by adjusting the resistance encountered by the wings 28 in a manner described above.

It is to be understood that the invention is not limited to the heretofore described 80 means for driving the discharger, as such means might be replaced by any appropriate known device such for instance as steam or compressed air turbines, or electric motor, whose rotor or armature would be keyed 85 on axle 14 and surrounded by the stator or field supported by the centrifugal frame, the speed being regulated by regulating the steam, compressed air or current, all of which requires no further explanation. If 90 a forced drive at constant speed be desirable a suitable gearing may be used.

The invention is not limited, of course, to the particular wedge-shape lugs 31, as these may consist of vertical fingers whose upper 95 ends engage the rear face of the wings 28, exerting thus exactly the same action as the wedge-shape lug. Similarly the slots 33 and corresponding keys 32 may be helical instead of strictly longitudinal and so disposed that when the organ 30 is raised it is compelled to turn slightly around axle 14 towards the wings 28 thus quickening and extending the action of the lugs on said wings. The frames 16, 17 and 18 constituting mere means to support the blades 19 and connect them to the sleeve or hollow axle 14, may be replaced by any suitable device, such for instance as a complete circular basket connected by its bottom to the lower 100 end of sleeve 14 and having the blades 19 attached to the outer surface of its vertical wall. In this case the annular trough 23 can be attached to the inner periphery of the discharger basket while the bowl 20 and pipes 110 22 can be dispensed with, the massecuite from spout 21 dropping then directly on the bottom of the discharger basket and issuing therefrom through openings corresponding to the lowermost blades 19 exactly as described 115 120 relatively to the pipes 22.

Referring more particularly to Figures 7 and 8, the discharger basket consists as heretofore of a bottom plate 41 attached to the lower end of the hollow shaft or axle 14 surrounding the centrifugal spindle 1, and of a vertical wall 42, to the outer surface of which are attached the discharger blades 19, in the same position relatively to the filtering basket 3 as described before. From the 125 130

bottom 41 rise two vertical partitions 43 and 44, extending all the way across the bottom and having their extremities connected to the wall 42 a short distance from one another, as seen in Figure 8 whereby to present openings 45, the disposition being such that the latter discharge right behind the lowermost blades 19. The location of the partitions 43 and 44 is such that the massecuite admitted through spout 21 must fall within the area circumscribed between said partitions; the height of these is sufficient to retain the received massecuite and deflect it toward the openings 45 while the shape of the partitions 15 is such that at any point the angle formed by the partition and the direction of the centrifugal force is such as not to prevent the massecuite from reaching the openings 45. It is thus seen that the massecuite drops 20 directly from the spout 21 on to the bottom 41, is then thrown to the periphery by the centrifugal force, being directed by the partitions 43 and 44 toward the openings 45 through which it issues from the discharger 25 basket to be deposited against the wall of the filtering basket 3 in the empty space just formed by the lowermost blades 19.

The washwater gutter 46, similar to the gutter 23 already described is built directly 30 against the inner surface of the wall 42, this latter forming thus the outer wall of the gutter. In this outer wall minute perforations 47 are formed all around the periphery or at suitable intervals. The water 35 received from the feed pipe 48, is thus forced by the centrifugal power through the perforations 47 and sprayed upon the sugar as described above.

The wall 42 of the discharger basket is 40 not necessarily a solid wall, but may be open work or of any system of uprights and braces as will give it adequate strength.

It will be appreciated from the foregoing that I have provided a continuously operating centrifugal of comparatively simple construction, in which the progress of the action 45 may be nicely regulated and wherein the separation of sugar may be carried out economically.

It is obvious that various changes and 50 modifications may be made in the details of construction and design of the above specifically described embodiment of this invention without departing from the spirit 55 thereof, such changes and modifications being restricted only by the scope of the following claims.

What is claimed is:

1. A centrifugal comprising a rotary 60 basket, driving means for the basket, a casing for collecting the liquid material surrounding the basket, means for collecting the solid material continuously from the interior of the basket, blades moving adjacent the inner wall of the basket and re-

ceiving their movement from the basket driving means, and air-resistant means for varying the speed of said blades, substantially as described.

2. A centrifugal comprising a basket, 70 means for driving the basket, lifting means within the filtering wall of the basket adapted to move the massecuite progressively along such filtering wall, means for collecting the separated materials, means whereby 75 said lifting means are driven from the basket driving means, and an air-resistant device for slowing the motion of said lifting means, and means to regulate said air-resistant device, substantially as described. 80

3. A centrifugal comprising a rotary basket, driving means therefor, blades moving adjacent the filtering wall of the basket, 85 said blades being caused to rotate with the basket by the presence of the massecuite, wings moving with said blades and exposed to the air whereby to slow the movement of the blades relatively to the basket, and means for deflecting said wings to increase or diminish the air-resistance substantially 90 as described.

4. A centrifugal comprising a rotary basket, blades moving inside the wall of the basket and inclined to lift the massecuite upwardly along said wall, means for rotating the basket and said blades, pivoted wings moving with the blades, and adjustable cams engaging said blades acting to deflect the same to adjust the air-resistance. 100

5. A centrifugal comprising a casing divided into upper and lower portions with means for carrying off material separately from such upper and lower portions, a centrifugal bowl mounted for rotation within said casing having a perforated wall, means 105 for positively rotating said bowl, a frame mounted within the bowl and for independent rotation, inclined blades carried by said frame adjacent the perforated wall and acting to lift the material in the bowl upwardly 110 along the perforated wall, means for introducing the material to be separated at the base of the bowl and at the outer portion thereof beneath the blades whereby fluid material will be thrown out into the lower portion of the casing, the material within the bowl adapted to be rotated therewith and to cause rotation of the frame by reaction upon said blades, means for braking the movement of the frame and blades to variable degrees during the rotation of the bowl and frame, and means rotating with the frame and within the upper portion of the bowl for spraying fluid upon the material in the bowl which has reached a level 115 with the upper portion of the casing, and means for catching the separated material from the top portion of the bowl. 120
